United States Patent Office

Des. 214,793
Patented July 29, 1969

214,793

LASER

J. Perry Smith, Hawthorne, and Ulf R. Helgesson, Woodland Hills, Calif., assignors to TRW Inc., Redondo Beach, Calif., a corporation of Ohio

Filed Mar. 11, 1968, Ser. No. 10,917

Term of patent 7 years

Int. Cl. D14—99

U.S. Cl. D26—14

Fig. 1

Fig.2

Fig. 3

Fig. 4

Fig. 5

FIGURE 1 is a top front perspective view of a laser showing our new design;

FIGURE 2 is a bottom rear perspective view thereof;

FIGURE 3 is a front elevational view thereof;

FIGURE 4 is a top plan view thereof; and

FIGURE 5 is a left end elevational view thereof.

The dominant features of our new design are shown in solid lines.

We claim:

The ornamental design for a laser, substantially as shown and described.
